UNITED STATES PATENT OFFICE.

JOHN F. COURSON, OF PITCAIRN, PENNSYLVANIA.

DRAFT-GEAR.

1,095,818.

Specification of Letters Patent.

Patented May 5, 1914.

Application filed January 13, 1913. Serial No. 741,643.

To all whom it may concern:

Be it known that I, JOHN F. COURSON, a citizen of the United States, residing at Pitcairn, in the county of Allegheny and State 5 of Pennsylvania, have invented certain new and useful Improvements in Draft-Gears, of which the following is a specification.

My invention relates to the class of draft gearing or rigging for railway cars, etc., and 10 has for its object to provide a draft gear of simple construction adapted for easy insertion in or removal from the usual car framing, whereby it is, when so installed, operable to perform its several intended 15 functions, and whereby the gear may be readily removed for repair or any other purposes and again inserted without disarrangement of the frame.

The gear, as shown, is of the friction type, 20 embodying a casing or cylinder and contained friction-creating elements operable by the action of a central wedge and supplemental expanding wedges and friction shoes adapted to engage the inner face of the cylinder, of any suitable type and not therefore illustrated in detail.

The present invention relates particularly 25 to the removable mounting of the gear and its parts as a whole, and the connection between the frictional casing and the drawbar.

While the gear and its parts is adapted 30 for incorporation with the usual standard steel underframe construction, it is readily capable of use with and adaptation to any 35 other approved type of framing.

In the drawings illustrating preferred arrangements of the invention—Figure 1 is a longitudinal sectional view, partly in elevation, showing the apparatus in normal 40 position, indicated by the section line I. I. of Fig. 2. Fig. 2 is a horizontal sectional view, indicated by the section line II. II. of Fig. 1. Fig. 3 is a vertical cross sectional view, indicated by the line III. III. of Fig. 2. Fig. 4 is a perspective detail view of the friction casing, detached. Fig. 5 is a similar view of one of the connecting arms for the drawbar and cylinder. Figs. 6 and 7 are 45 sectional views, similar to Figs. 1 and 2 illustrating modified constructions. Fig. 8 is a similar sectional view showing a further modified construction, providing removable abutments for the follower. Fig. 9 is a cross

section on the line IX. IX of Fig. 8. Fig. 10 is a detail sectional view in plan, showing the reinforced bearing for one of said abutments, taken on the line X. X. of Fig. 8.

The drawings show the invention as applied to the structural framing of a car embodying the customary center sills 2, 2, arranged at each side of the normal center of the frame and gear, having the usual top and bottom plates 3, 4, and if desired, an end sill, not shown.

The drawbar 5 extends through the usual 65 front opening in the end sill, having any necessary supporting element at the front of any suitable construction and which is not necessarily herein described, the drawbar being preferably enlarged at its rear 70 portion to provide a rear abutting terminal 6, preferably rectangular in construction.

It will be understood that the equipment is not necessarily dependent upon any particular construction or type of friction-producing or shock-absorbing mechanism. I have not therefore indicated such in detail, but show at the rear portion of the apparatus a cylinder of casing 7 which may be understood to represent generally the casing of 80 any suitable friction or spring mechanism, or both, constituting the main shock-absorbing member of the apparatus.

Casing 7 abuts by its rear end against a substantial back stop 8 mounted between the 85 side members 2 constituting the center sill, by bolts or rivets 9, or in any other suitable manner. The casing rests by its bottom upon an under cross supporting bracket or strap 10, secured in any convenient way, as 90 by bolts or rivets 11, to the bottom plate 4.

Casing 7 is provided at each side with laterally extending gudgeons or housings 12, 12, providing longitudinal receiving openings 13 for the rear ends of connecting arms 95 or links 14. Said arms are provided at their rear ends with enlarged heads or abutments 15, of suitable construction, and which are so designed as to fit neatly against the opposite sides of the casing 7, and to bear forwardly against the rear portions of housing abutments 12, as clearly shown.

The rear portion 6 of drawbar 5 abuts, either directly or through any intervening construction, against a vertically arranged 100 follower 16, which in turn is arranged to en-

gage and transmit either buffing or pulling strains to or from the element or elements of the contained friction mechanism, as a central expanding wedge 17, shown in dotted lines. The mounting of said wedge in the casing and its connection or engagement with the follower may be in any preferred or suitable manner and does not necessarily form any part of the present invention. 19 Follower 16 engages, by its front terminal faces, resisting brackets 18, 18, rigidly secured to the center sill framing in any suitable manner, as by bolts or rivets, 19, connecting the brackets with plates 3 or 4. 15 The rear portion 6 of drawbar 5 is transversely apertured, as indicated at 20, for the reception of a transverse key 21, extending outwardly beyond the drawbar at each side thereof, as clearly shown. The forward 29 ends of connecting arms 14 are similarly apertured and engage the end portions of drawbar key 21, cotter pins or other suitable devices 22 being used to retain the parts in operative position. Any space between the 25 sides of the drawbar and arms 14 is preferably occupied by suitable fillers or washers 23.

In the use of the construction with the ordinary or any suitable friction or spring 30 gear, or either, embodied with casing 7, the follower 16 will be normally pressed forward against brackets or abutments 18 and against the rear end 6 of drawbar 5, as clearly shown in Figs. 1 and 2, holding the 35 drawbar outwardly in normal position for coupling, the rear end of the casing bearing backwardly against abutment 8.

For the purpose of inserting the follower 16 without removal of stop abutments 18, 40 the bottom plate 4 may be cut away, as indicated at 24, the opening being closed by a supplemental cover plate 25, preferably held in position by bolts 26.

The operation of the gear as thus constructed will be readily apparent. In buffing, the drawbar will travel backwardly, carrying with it follower 16, arms 14 at the same time sliding freely backwardly through openings 13, follower 16 forcing the wedge 50 17 and the other pressure-absorbing elements of casing 7 into operative engagement, the pressure being absorbed and counteracted by the back stop or abutment 8 against which the casing bears. In pulling, the drawbar 55 key 21 will impart forward movement to arms 14, which in turn draw the casing 7 and its contents forwardly by housings 12 against the relatively stationary follower 16, stop abutments 18 transmitting the pulling 60 strains to the car framing.

While I have shown the follower 16 and arms 14 as arranged vertically, it will be understood that these parts may be arranged horizontally, the opening 20, key 21 and 65 stops 18 being correspondingly arranged

vertically, the parts operating in the same manner as above described. Figs. 6 and 7, however, show such alternative arrangement, but modified as to the connection of the arms 14^a with the drawhead 5^a, 6^a, and secured thereto by rivets or bolts 21^a. The follower 16^a bears forwardly against stop abutments or brackets 18^a secured to the side sills 2^a, the bottom plate 4^a being cut out, if desired, in the same manner as shown in Fig. 1. The 70 75 construction and operation of the parts is otherwise substantially the same as above described, the corresponding parts being numbered accordingly, with the exponent ^a.

Figs. 8 and 9 show the follower 16^b bearing forwardly against resisting cross bars 18^b, 18^b, extending across through suitable receiving openings 27, secured by cotters 22^b, bearing by their ends against the center sills 2^b, 2^b, and against reinforcing abutments 28 85 90 preferably provided and secured to the sills in any suitable manner, as by rivets 29. The bar 18^b provides a substantial bearing for the inner head 6^b of the drawbar, on which it may slide longitudinally, the front or coupling end of the drawbar being suitably supported on the end sill, or otherwise as preferred. Such front support may also be removably attached, as by bolts, enabling the entire interior space of the under frame to 95 be exposed. By this arrangement I am enabled to readily erect or remove the entire installation by merely withdrawing the cross bars 18^b, whereupon the entire gear and its parts may be readily removed from the 100 framing. The other parts of the gear are substantially the same as heretofore described, the parts being indicated by corresponding numerals having the exponent ^b.

The inherent advantages of the invention 105 will be readily appreciated by all those accustomed to this class of devices. It will be observed that the entire gear is positioned within or between the center sills and that there is no cutting thereof required, the construction facilitating the mounting or removal of the entire gear with comparative ease and economy of time. This is of considerable advantage in initial equipment or in connection with repairing any of the 110 parts. The several parts are so constructed and assembled as to be readily placed in the car framing; the transmission of the strains against the back stop and front abutments 115 imparts the strains directly to the main central member of the car underframe; the several parts are of simple, cheap and easy construction, and readily inserted or connected or disconnected without the necessity of skilled labor. There is no weakening of the 120 several parts, and the transmission of the various forces and strains is direct and positive, while the connection between the casing 7 and the drawbar avoids the necessity of the usual surrounding strap construction, 130

while facilitating replacement or repair of the arms without affecting the casing or its parts.

What I claim is:

1. In combination, a slidably mounted gear casing provided with apertured housings, a drawbar, arms connected to said drawbar, said arms extending rearwardly from said drawbar through said apertured housings and having rear terminal abutments adapted to engage therewith to effect forward travel of the casing with the drawbar and to move rearwardly with the drawbar independently of the casing.
2. In a draft gear, the combination with the car framing, of a shock-absorbing member having laterally extending apertured housings, a drawbar, arms fixedly connected with the drawbar passing through said housings and having rear terminal abutments, a follower interposed between the shock-absorbing member and the drawbar, and re-
3. In a draft gear, the combination with the car framing having lateral openings therein and supplemental reinforcing abutments, of a shock absorbing member having laterally extending apertured housings, a drawbar, arms fixedly connected with the drawbar passing through said housings and having rear terminal abutments, a follower interposed between the shock-absorbing member and the drawbar, and resisting cross-bars for the follower extending through said openings in the car framing and bearing against said abutments.

In testimony whereof I hereunto affix my signature in the presence of two witnesses.

JOHN F. COURSON.
